UNITED STATES PATENT OFFICE.

WILLIAM I. MORGAN, OF SEAFORD, NEW YORK.

SEPARATOR.

1,091,947.

Specification of Letters Patent. Patented Mar. 31, 1914.

Application filed May 22, 1911. Serial No. 628,865.

To all whom it may concern:

Be it known that I, WILLIAM I. MORGAN, a citizen of the United States, and a resident of Seaford, county of Nassau, and State of New York, have invented certain new and useful Improvements in Separators, of which the following is a specification.

This invention relates broadly to apparatus for separating liquid from solid constituents of a material containing both, and more particularly to apparatus for extracting oil, grease, water, etc. from garbage or other matter.

The objects and advantages as well as the construction and operation of the apparatus constituting the present invention will be fully understood from the following description of preferred embodiments thereof, taken with the accompanying drawings illustrating such embodiments and in which drawings,—

Figure 1 is a view of an apparatus embodying the present improvements, showing the container outside of and in position to be moved into the casing and showing one end of the casing broken away. Fig. 1^a is a detail view of a form of one end of the casing adapted to permit the use of a means for pulling the container into the casing. Fig. 2 is a vertical transverse section of the apparatus with the container in place in the casing. Fig. 3 is a transverse sectional view of the container, open for the discharge of its contents. Fig. 4 is a like view of the container, closed. Fig. 5 is a plan view of one end of the container. Fig. 6 is an elevation of a part of the same, on a larger scale than Fig. 1. Fig. 7 is a section on the line 7—7 of Fig. 3. Fig. 8 is a detail view in side elevation of the container support which is mounted at the mouth of the casing. Fig. 9 is an end view of a part of the same and Fig. 10 is a transverse sectional view exemplifying a different form of container which may be employed.

Like characters of reference designate like parts in the several views.

In order to carry into practice one of the most important features of the present invention, the apparatus essentially includes an outer vessel B and an inner container A whose interiors conjointly form the treating chamber of the apparatus, the material undergoing treatment being supplied to the interior of said vessel and container through

an inlet, as the drum C having a valve D, with which the vessel is provided and said vessel having between said inlet and the container a space which contains a part of the mass of material undergoing treatment 60 and whose wall is fluid tight, the container being open to said space and having its wall also spaced from the confronting wall of the vessel and formed to permit the egress of fluid to the latter space and to retain the 65 solid constituents of the material undergoing treatment. The vessel also has an inlet E for the steam or other fluid employed to treat the material and this inlet is so arranged that that portion of the material 70 which is outside of the container (that is to say, is in the space between the container and the material-inlet) first receives the treating fluid, and as the wall of said space is fluid-tight, the fluid passes through the 75 portion of the material referred to and into the portion of the material which is in the container, before it finds an outlet from the material through the wall of the container. Preferably the container A occupies approximately the lower half only of the vessel 80 B, as shown, but it may extend somewhat higher than this or have its open end terminate below the illustrated place, without departing from the spirit of this part of the 85 invention. This correlation of parts, with the use of a treating fluid under pressure adequate for the purpose, causes the extraction of substantially all of the liquid contained in the material undergoing treatment 90 and the compacting of the solid residue of said material into the container. To provide for the removal of said solid residue from the apparatus, the vessel and container are removable one from the other (the container preferably being the removable member) and the container has provision for the discharge therefrom of said solid residue. In a general way this constitutes one of the 95 most important features of the present invention, but as will hereinafter more clearly be understood, the invention embodies particular features in respect of the construction of the container and other parts, and combinations and correlation of elements 100 which are herein claimed irrespective of the particular correlation hereinbefore set out somewhat in detail.

A designates the preferred form of container embodying the present improvements. 110

This container may be of any suitable shape, size and material. It is essentially formed to permit the liquid content of the material undergoing treatment and the steam or other fluid employed for the extraction of said content to flow therefrom; and also to retain the residue, that is, the solid matter from which the liquid ingredients have been extracted and to permit said residue to be quickly discharged therefrom.

The particular forms of containers herein exemplified have many other special and important features for the purpose of the present invention and will be described herein in detail, without, however, intending thereby to restrict the invention to the particular forms illustrated, as many changes may be made in the construction of the container without departing from the spirit of the invention or the scope of the subjoined claims.

The container A comprises two sections a a' which are, respectively, pivotally connected at 20 and 21 to a fixed frame member 22 which extends longitudinally of the container along the top of the latter and adjacent to the upper inner corners of the sections. The frame of each section comprises an upper longitudinal member 23 at the outer side thereof; a lower longitudinal member 24 at the outer side thereof; a series of connecting members 25 disposed along the length thereof and each extending from the member 23 to the member 24; a series of longitudinal outside members 26; spaced transverse members 27 at the top; a transverse member 28 at each upper end, see Fig. 5, which may be an extension of the member 23, and members 29 connecting the members 28 with the members 25^a at the ends of the sections. The side wall of each section is marked 30 and the end wall thereof is marked 31. These walls are preferably formed of perforated sheet or plate metal. In form the container is preferably semi-cylindrical or trough-shaped, in cross section. The frame-members 25 are accordingly shown as being of segmental form and the side walls 30 similarly are of the form of segments of circles. These walls are shown as arranged outside the members 25 and as having their longitudinal edges braced by the members 23 and 24 which are arranged outside said walls and at the upper outer corner and lower corner of the sections, respectively. The side walls are further braced by the members 26, and these members serve an additional important function, in the illustrated embodiment of the invention, as will be hereinafter explained. The members 27 have their outer ends secured to the members 23 while their inner ends are sleeved upon the rods 20 and 21, about which the sections turn in opening and closing the container. The ends of the

container are preferably convex and the members 28 are of corresponding form; the members 29 extending curvilinearly from the members 28 to the members 25^a. The members 28 are preferably provided with sleeves 32 pivotally mounted on the rods 20 and 21 in order to provide pivotal support for the sections at the ends of the latter.

33 and 34 designate fixed perforated or porous walls which are spaced from each other and are so arranged as to form inner longitudinal walls of the respective sections a and a' when the latter are closed. The upper ends of these walls are secured to a frame member 35 which extends longitudinally of the container and is arranged beneath the frame member 22. This container is frequently made of considerable length, its capacity in certain cases being several tons of material. It is therefore advisable to divide it longitudinally as well as transversely. This longitudinal division of the container is illustrated in Fig. 6 in which a^x designates one portion of a section and $a^{x'}$ designates the other portion of said section. It will be noted that the members are separated from each other on lines which break joints. It is necessary that the container herein described be incased while the liquid constituents of the material undergoing treatment are being extracted. The incasing means, herein shown, is formed by a vessel B separate from the container. This vessel may be of any suitable construction, shape and size. The one herein shown is cylindrical and is arranged in an approximately horizontal position. It is provided with a drum C through which it is charged with material to be treated. This drum has a valve D for controlling the passage of the material therethrough. In the present exemplification of the invention, steam for extracting purposes is derived from a suitable source of supply not shown and is delivered by means of a valved pipe E to the drum C at a place between the vessel B and the valve D. The vessel also has its ends provided with movable closures, as hinged doors F and G.

In practice, with this particular form of the invention, the container A is inserted into the vessel B. A charge of material is then delivered to the vessel through the drum C. When a sufficient amount of material has been received by the vessel and container, the charge being preferably such as to reach to a point in the drum at or immediately below the pipe E, the valve D is closed and steam is admitted through the pipe E. This steam preferably is under pressure adequate to extract the liquid content of the material and to compress the solid matter or residue of the material. When the liquid ingredients of the material in the vessel have been thus extracted, the

steam is cut off and the valve D is again opened and more material is supplied. The valve C is then closed and the steam is again admitted. This is continued until the container has been filled with solid matter, that is to say, with matter from which liquid ingredients have been extracted.

In the extracting operation, the liquid matter and the steam flow through the walls of the container and into the space between the container and the inner wall of the vessel, to the bottom of the latter, and the vessel is drained thereof through the pipe H shown in Fig. 1. It will be noted that the members 26 of the container engage the inner wall of the vessel B, and in order that these members will not interfere with the flow of the liquid and steam around the container and to the bottom of the vessel A, each has its outer edge provided with notches 36, as shown in Fig. 6.

To facilitate the transfer of the container A to and away from the vessel B, a suitable movable carrier is provided. The carrier is shown as of an overhead traveling nature comprising suitable wheeled members, I, I, which travel on a track J and are connected by chains or other suitable flexible connectors with the container. In the herein exemplified form, each connector comprises a chain having members 37 which are connected to eyes 38 on the frame-members 27 of the container, and extend thence convergently to a common member 39 which is fastened at 40 to the carrier. One end of the chain 41 is connected to the eye 42 on the plate or strong-back 22, and the other end to the differential block 43. When the block 43 is released, the weight in the container will cause same to open and discharge its contents; see Fig. 3. Or, if desired, the chains 41 may be held fast and the members 39 may be raised by suitable means which pull upon the separate chains 37, and raise each half of the container and open the same, as shown.

To facilitate the introduction of the container into the vessel B, a support K (see Figs. 8 and 9) is arranged at the mouth of the vessel. This support comprises a shaft 45 supported by standards 46, having bearings 47, in which the shaft is mounted to turn, and the shaft is provided with brackets 48, which carry the wheels 49 upon which the container may be moved into and out from the vessel B, when the door F of the vessel is open. The wheels 49 are so disposed as to engage suitable members 26 of the container, preferably the lowermost ones, and are shown as being mounted on axes which are inclined to accord with the position of said members. The door F is provided with a ledge, 50, and the interior of the container is provided at opposite sides with ledges 51 and 52. These ledges form

tracks upon which the container is supported when in the vessel B. The bottom of the vessel B is provided with rollers 53 which preferably are incased in pockets 54 and engage the members 24 of the container and enable it to be readily moved into and out of the vessel B.

The shaft 45 is provided with a lever or handle 55 by which it may conveniently be turned to raise the wheels 49 to operative position across the mouth of the vessel B, or to lower them to a position below the plane of the door or closure F, in order that the support will not interfere with the opening or closing of the latter.

If desired, a cable or other suitable means, designated 56 in Fig. 1^a may be provided for convenience in drawing the container A into the vessel B, and a like means may be provided at the other end for drawing the container out of said vessel: it being of course understood that the chains are detached from the container, and attached thereto, one after another, as the container is drawn into and out of the vessel, respectively. As shown in Fig. 1^a the cable may extend through a passage in the head, said passage being preferably provided with a valve, as shown at 57, for closing it.

In Fig. 10 a slightly changed form of container is indicated. This container, which is marked A', has its two sections a^{10} and a^{11} hingedly connected at their upper edges to longitudinal frame elements 123, 123, as shown at 120 and 121, respectively. Each of these sections is provided with a perforated or porous side wall 130, perforated end walls 131 and inner perforated or porous side walls 133 and 134. The walls 133 and 134 are spaced apart from each other and those of the section a^{10} are spaced from the corresponding walls of the section a^{11} . In this form the outer longitudinal members (marked 126) corresponding to the members 26 of the other form are set with their flanges instead of their corners against the wall but it will be understood that either form of container may have either of the illustrated arrangements of such members, or any other suitable arrangement or form thereof, without departing from the spirit of the invention. The frame members 123 are connected with each other by fixed transverse angle-members spaced along the length thereof, one of which is shown at 127. The members 133 and 134 of each section are secured to the web of a T-iron 135. These T-irons are spaced apart from each other and extend longitudinally of the container and are secured to the flanges of the transverse members 127.

Having now described the invention what I believe to be new and desire to secure by Letters Patent, is:

1. In an apparatus of the class described, a container having a wall adapted to retain solid matter and to permit fluid to pass therethrough, said container having its body 5 divided longitudinally and the sections on opposite sides of its line of division hingedly mounted to open outwardly away from each other, combined with a casing which extends around and above the container, the container fronting walls of the container and casing being separate from each other and the portion of the casing above the container forming a chamber for material to be treated and having an inlet for said material and an inlet 10 for a treating fluid, the container being open to said chamber and the casing and container being relatively movable to expose the latter.

2. An apparatus for extracting liquid constituents and compacting the solid residue of a material containing the same, comprising an outer vessel having in its side a combined inlet for the material and for the fluid for treating said material, and a container arranged in said vessel with a space between the confronting walls of the vessel and container and also a space between the container and the fluid inlet substantially equal in size to the container, the wall of the latter space being fluid tight, said container being open to said latter space and having its wall formed to retain solid constituents of the mass undergoing treatment and to permit liquid to pass through it to the first mentioned space, said first mentioned space having means for the outlet of fluid therefrom, the vessel and container being relatively movable longitudinally to expose the container and said container being formed 30 of oppositely movable hingedly-mounted longitudinal sections for the discharge of the treated material therefrom.

3. In an apparatus of the class described, a container comprising a plurality of hingedly-mounted oppositely-movable longitudinal sections having longitudinal and transverse walls, fixed inner walls extending longitudinally of the container between said sections and spaced from each other, 45 said walls being adapted to permit liquid to pass therethrough and to retain solid matter, and a casing for said container, the casing and container being relatively movable to expose the latter and having their confronting walls disposed in a spaced relation when they are relatively arranged in operative position.

4. In an apparatus of the class described, a container comprising a plurality of relatively movable sections whose walls are adapted to permit liquid to pass therethrough and to retain solid matter, a casing for said container, the casing and container being relatively movable to expose the latter and of diameter such as to provide a

liquid-receiving space between their walls, and longitudinal members in said space serving to maintain said relation, and to divide said space into a plurality of channels extending substantially continuously 70 lengthwise of the container, said members being interrupted to permit the liquid to flow past the same from one channel to another.

5. In an apparatus of the class described, an approximately horizontal upwardly-open container whose body is formed of a plurality of relatively movable sections extending longitudinally thereof and having walls formed to permit liquid to pass therethrough and to retain solid matter, a casing for said container, the casing and container being relatively movable in the direction of their lengths to expose the container and of such relative diameter as to provide a liquid-receiving space between their confronting walls and a material-receiving space above the open side of the container, the latter space having means for the inlet of material and a treating fluid to the interior of the apparatus, and means in said liquid-receiving space for maintaining the confronting walls of the casing and container in spaced relation and dividing the liquid-receiving space into a series of approximately horizontally-disposed substantially continuous channels extending lengthwise of the container and having communication with each other for the flow of liquid from one to another, said means comprising a plurality of longitudinal members having interruptions. 85 90 95 100

6. In an apparatus of the class described, a casing having diametrically opposite longitudinal ledges, a container having flanges which engage the ledges, said casing and container being relatively movable longitudinally to expose the latter and having their walls relatively arranged to provide a liquid-receiving space around the latter, the ledges and flanges serving to close one end 105 of said space and to support the container, the container being adapted to permit liquid to pass to said space and to retain solid matter and the casing having means through which it is supplied with material to be treated and an inlet for the fluid for treating said material. 110 115

7. In an apparatus of the class described, an upwardly-open container having its body divided longitudinally and the sections on opposite sides of the longitudinal division hingedly mounted to open outwardly away from each other, said container having its wall formed to permit fluid to pass through it and to retain solid matter, combined with a casing, the casing and container being relatively movable longitudinally and having such relative diameters that a liquid-receiving space will be left between their confronting walls and a material-receiving space will 120 125 130

- be provided above the open-side of the container when they are in operative relation with each other, the casing having means for the inlet of material and treating fluid to 5 the material-receiving space, and coöperating means on the casing and container, disposed longitudinally thereof and serving to close direct communication of the liquid-receiving space with the material-receiving 10 space above the container.
8. In an apparatus of the class described, an upwardly-open container having its body divided longitudinally and the sections on opposite sides of the longitudinal division 15 hingedly mounted to open outwardly away from each other, said container having its wall formed to permit fluid to pass through it and to retain solid matter, combined with a casing, the casing and container being relatively movable longitudinally and having 20 such relative diameters that a liquid-receiving space will be left between their confronting walls and a material-receiving space will be provided above the open-side of the container 25 when they are in operative relation with each other, the casing having means for the inlet of material and treating fluid to the material-receiving space, ledges extending longitudinally of the casing between the 30 material-receiving space and liquid-receiving space of the latter, flanges extending from the upper outer sides of the container for engaging said ledges, the ledges and flanges cooperating to support the container 35 and close direct communication of the liquid-receiving space with the material-receiving space, and supporting means for the container, arranged below said ledges and flanges, said supporting means comprising 40 rollers.
9. In an apparatus of the class described, the combination with a casing and a container, the casing having elements disposed longitudinally thereof for supporting the 45 container and having an end closure, and the container being movable longitudinally of the casing upon said supporting elements, of means arranged outside the casing for supporting the portion of the container which 50 protrudes from the casing, the container being movable upon said means in its travel into or out of the casing, the latter supporting means comprising a shaft journaled in a support and means fixed on the shaft and 55 projecting therefrom for engaging the container, the shaft being adjustable pivotally in its bearings into and out of operative position.
10. In an apparatus of the class described, 60 the combination with a casing and a container, the container having its wall provided with apertures and with longitudinal stiffening elements, said wall being thereby adapted to permit fluid to pass therefrom 65 and to retain solid matter, and the casing
- having its interior provided with elements arranged longitudinally thereof for supporting the container and also having a closure, and means arranged outside of said closure for supporting the end of the container which protrudes from the casing while the container is being moved into or out of the casing, said means comprising a shaft which is pivotally adjustable in its bearings, and means projecting therefrom 70 and carrying rollers which are adapted to engage stiffening elements of the container when the shaft has been adjusted to position to place said rollers in operative relation with the container, the adjustment of the shaft adapting the rollers to be adjusted out of the path of the container, when desired.
11. In an apparatus of the class described, a casing having closures at its opposite ends, one of said closures being movable, said casing also having container-supporting means extending longitudinally thereof, combined with a container movable longitudinally of the casing upon said supporting means, and means provided upon one of the closures to support the container in moving it in and out of the casing, and independent means extending through the other closure and adapted to engage the container to move it longitudinally of the casing. 80
12. In an apparatus of the class described, a casing and a container adapted to be received by the casing, with a space between their walls, the container being adapted to retain solid matter and to permit liquid to pass to said space, the container being relatively movable with respect to the casing to expose the container and said container being longitudinally divided to form complementary sections and having a longitudinal frame to opposite sides of which the upper ends of said sections are hingedly secured so as to open outwardly away from each other, the lower confronting edges of said 90 sections bearing upon releasable means for securing the sections in operative position. 100
13. In an apparatus of the class described, a casing and a container adapted to be received by the casing with a space between their walls, the container being adapted to retain solid matter and to permit liquid to pass to said space, the casing and container being relatively movable to expose the latter and said container comprising a frame 110 and sections hingedly secured to the frame at their upper ends and adapted to open oppositely, said container having longitudinally extending members outside the walls thereof adapted to stiffen said walls and to hold the same in a spaced relation from the wall of the casing. 115
14. In an apparatus of the class described, a casing and a container adapted to be received by the casing with a space between 120
- 125
- 130

their walls, the container being adapted to retain solid matter and to permit liquid to pass to said space, the casing and container being relatively movable to expose the latter and said container comprising a frame and sections hingedly secured to the frame at their upper ends and adapted to open oppositely, said container having longitudinally extending members outside the walls thereof adapted to stiffen said walls and to hold the same in a spaced relation from the wall of the casing.

15. In an apparatus of the class described, a casing and a container adapted to be received by the casing with a space between their walls, the container being adapted to retain solid matter and to permit liquid to pass to said space, the casing and container being relatively movable to expose the latter and said container comprising a frame and sections hingedly secured to the frame at their upper ends and adapted to open oppositely, said container having longitudinally extending members outside the walls thereof adapted to stiffen said walls and to hold the same in a spaced relation from the wall of the casing, the casing having means for the discharge of the liquid therefrom and the stiffening members of the container having interruptions to permit the liquid to pass to said discharge means.

16. In an apparatus of the class described, a casing and a container adapted to be received by the casing, with a space between their walls, the container being adapted to retain solid matter and to permit liquid to pass to said space, the casing and container being relatively movable to expose the latter and said container comprising a frame and sections hingedly secured to the frame at their upper ends and adapted to open oppositely, said container having longitudinally extending members outside the walls thereof adapted to stiffen said walls and to hold the same in a spaced relation from the wall of the casing, the casing having means for the discharge of the liquid therefrom and the stiffening members of the container having interruptions to permit the liquid to pass to said discharge means.

17. In an apparatus of the class described, a casing and a container adapted to be received by the casing, with a space between their walls, the container being adapted to receive solid matter and to permit liquid to pass to said space, and being longitudinally divided to form complementary sections, and comprising a longitudinal frame member, members carrying the walls of the respective sections, said sections being pivotally secured to opposite sides of said longitudinal frame member at their upper inner ends, releasable means at the lower inner ends of

the sections for securing them in holding position, and means attached to the longitudinal frame member for transporting the container.

18. In an apparatus of the class described, a casing and a container adapted to be received by the casing, with a space between their walls, the container being adapted to retain solid matter and to permit liquid to pass to said space, said container being movable into and out of the casing and comprising a fixed frame extending longitudinally thereof, a pair of oppositely movable sections hingedly connected at their upper ends to said frame and fixed longitudinal walls secured to said frame and extending into the space between said sections, the fixed walls being spaced from each other and adapted to permit liquid to flow through them into the space between them.

19. In an apparatus of the class described, a casing and a container adapted to be received by the casing, with a space between their walls, the container being adapted to retain solid matter and to permit liquid to pass to said space, said container being movable into and out of the casing and comprising a fixed frame having a member extending longitudinally thereof and provided with spaced depending walls adapted to permit liquid to pass therethrough into the space between them, and other frame members which are secured to the first mentioned walls of the container and are hingedly connected at their upper inner corners to opposite sides of said fixed frame member.

20. In an apparatus of the class described, a casing and a container adapted to be received by the casing, with a space between their walls, the container being adapted to retain solid matter and to permit liquid to pass to said space, said container being movable into and out of the casing and comprising a fixed frame having longitudinal members arranged in a spaced relation and provided with walls which are adapted to permit liquid to pass to the space between them, said frame also comprising other members which are hingedly connected at their upper outer ends to opposite sides of the fixed frame and which carry the first-mentioned walls of the container.

21. In an apparatus of the class described, a casing and a container adapted to be received by the casing, with a space between their walls, the container being adapted to retain solid matter and to permit liquid to pass to said space, said container being movable into and out of the casing and comprising oppositely movable sections extending longitudinally thereof and each divided intermediate of its length.

22. In an apparatus of the class described,

a casing and a container adapted to be received by the casing, with a space between their walls, the container being adapted to retain solid matter and to permit liquid to 5 pass to said space, said container being movable into and out of the casing and comprising oppositely movable sections extending longitudinally thereof and each divided intermediate of its length, each section having 10 a frame provided with longitudinal members which are separated from each other on lines

which are vertically opposite from each other.

In witness whereof I have hereunto set my hand at the city of New York, county of 15 New York and State of New York this 18th day of May, 1911.

WILLIAM I. MORGAN.
